US0D1002110S

(12) **United States Design Patent** (10) **Patent No.:** **US D1,002,110 S**
(45) **Date of Patent:** **** Oct. 17, 2023**

(54) **FALSE EYELASHES**

(71) Applicant: **Yunxiao Tian**, Shandong (CN)

(72) Inventor: **Yunxiao Tian**, Shandong (CN)

(**) Term: **15 Years**

(21) Appl. No.: **29/886,240**

(22) Filed: **Mar. 7, 2023**

Related U.S. Application Data

(62) Division of application No. 29/858,226, filed on Oct. 28, 2022, now Pat. No. Des. 994,229.
